UNITED STATES PATENT OFFICE.

CALEB E. SUMMERS, OF KANSAS CITY, MISSOURI, ASSIGNOR TO LAURA A. SUMMERS, OF OAKTOWN, INDIANA.

CARBURETER.

1,180,334.

Specification of Letters Patent. Patented Apr. 25, 1916.

Application filed January 9, 1914. Serial No. 811,167.

To all whom it may concern:

Be it known that I, CALEB E. SUMMERS, a citizen of the United States, residing at Kansas City, in the county of Jackson and 5 State of Missouri, have invented certain new and useful Improvements in Carbureters; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to carbureters, and has for its principal object to provide a carbureter for use in multiple cylinder engines of the explosion type, whereby balanced and measured charges of fuel vapor 20 may be delivered to the various cylinders in proper sequence.

It is also an object of the invention, to provide a carbureter wherein fuel liquids of different specific gravity may be used, and 25 wherein the fuel liquid is measured before it enters the carbureter, and the measuring elements adapted for automatic adjustment to meet the varying requirements of the motor.

30 It is also an object of the invention, to provide a carbureter having a throttle for the fuel supply, together with means for automatically regulating the throttle and the fuel measuring elements by vacuum in 35 the intake manifold of the motor.

In accomplishing these and other objects of the invention, I have provided improved details of structure, the preferred forms of which are illustrated in the accompanying 40 drawings, wherein:

Figure I is a side elevation of an explosion engine equipped with a carbureter containing my improvements. Fig. II is a plan view of the same. Fig. III is an enlarged 45 side elevation of the carbureter. Fig. IV is a central, vertical section of the same on the line IV—IV, Fig. V. Fig. V is a plan view of the carbureter detached from the engine. Fig. VI is a plan view of the meas- 50

uring elements of the carbureter; the aux-

iliary valve chamber and measuring piston cylinder being removed. Fig. VII is a cross-section of the piston cylinder on the line VII—VII, Fig. III, showing the slotted portion overlying the vacuum conduit. Fig. 55 VIII is a transverse section of the measuring elements of the carbureter on the line VIII—VIII, Fig. III. Fig. IX is a vertical section of the liquid fuel measuring elements and their actuating mechanism on the line IX—IX, Fig. VI. Fig. X is a vertical section of the fuel selecting valve and part of the float mechanism on the line X—X, Fig. III. Fig. XI is a central vertical section of the selective valve for delivering 60 vapor to the various cylinders of the engine in proper sequence. Fig. XII is an inverted plan view of the valve seat. Fig. XIII is a detail perspective view of the valve plug. Fig. XIV is an enlarged vertical section of 65 the cylinder intake valve, showing a part of the manifold conduit and the vapor delivery pipe. Fig. XV is an enlarged elevation of the fuel heater; a part being broken away for better illustration. 75

Referring more in detail to the parts—1 designates the crank case, 2 the cylinders, 3 an intake manifold having branches 4 leading to independent cylinders, and 5 exhaust manifolds leading from the engine 80 cylinders 2; all of such parts being of ordinary and common construction.

Mounted on the intake manifold 3 is an auxiliary valve case plate 7, and suspended from the plate 7 is a valve casing 8 containing an automatic valve 9 of the type common in use as the auxiliary air valve of a carbureter, and which is adapted to lift against the tension of a spring 10 to admit air to the intake manifold of the engine 90 when the suction stroke of the piston creates a vacuum in the manifold and valve case sufficient to overcome the tension of the spring 10. 85

The case 8 contains the usual throttle 95 valve 12, which is operable by a rod (not shown) that may extend to a convenient position for the operator of the engine. Preferably cast integral with the valve case 8 and suspended therewith from the plate 7 is 100

a cylinder 14 containing a piston 15, the lower end of which contains a slot 16 that is adapted to register with the mouth 17 of a channel 18 leading through the wall 19, separating the cylinder from the valve chamber and opening into said chamber through a mouth 20, so that vacuum in the valve chamber is extended into the cylinder and tends to draw the piston downwardly toward the lower head of the cylinder and against the tension of a spring 21, which is connected with a lever arm 22 that is anchored at its outer end to a rod 23 adjustably mounted in an arm 24 on the cylinder, and has a hook 25 at its opposite end adapted for application to one of a plurality of apertures 26 in the lever arm 22, that is pivotally mounted in the cylinder and connected with the piston 15 by a link 28.

20 The lower head 30 of the cylinder 14 has a rod bearing 31, and slidably mounted in said bearing is a rod 32, the upper end of which has ball and socket mounting 33 in the piston 15, and the lower end of which projects into the measuring chamber 35 of a case 36 that is suspended from the cylinder 14 by cap screws 37.

25 The measuring chamber 35 communicates with a float chamber 39 containing a float 40, whereby a level of liquid fuel within the float and measuring chambers may be maintained through a valve mechanism comprising a lever 42, which is pivotally mounted in a bracket 43 on the bottom of the float chamber and has one end 44 adapted for engagement by the float, and its opposite end 45 adapted for engagement with the lower end of a valve stem 46, which projects through a bore 47 that communicates with a chamber 48 containing a valve 49, which is adapted for movement to and from a valve seat 50 in the base of the chamber, under tension of the spring 51, but for movement against the tension of said spring to open the port and admit liquid fuel to the float and measuring chambers. Opening into the valve chamber 48 is a channel 53, that is bored in the case 36 and adapted for communication with the channel 54 in the selective valve plug 55, which fits within the tapered bore 56 in an extension 57 on the case 36.

30 The channel 54 in the valve plug 55 extends transversely relative to the plug and is adapted for establishing communication between the bore 53 and either of two supply conduits 58—59, which lead to separate tanks 60—61 containing liquid fuel of different specific gravities, which we will designate as kerosene and gasoline, as they are preferred liquids for use in explosion engines.

35 The valve plug 55 also contains a channel

63, which is adapted for communication with a bleeding port 64 opening from the bottom of the float chamber and adapted for communication with said port when the channel 54 is out of communication with both of the supply conduits 58 and 59; the particular object of the bleeding port being to drain the float and measuring chambers. The valve plug 55 has a grip 65 on its upper end and carries a nut 66 on its lower end, against which a spring 67 bears to yieldingly retain the valve plug in its seat.

70 Opening from the measuring chamber 35, through a boss 70, is a channel 71 (Figs. VIII and IX), and opening from said channel are separate branches 72 and 73; the branch 72 having a conduit 75 leading to a heater 76, consisting of an inclosed cage mounted on and surrounding a pipe 77 on one of the exhaust manifolds, and preferably opening into the upper portion of the cage.

75 A conduit 78 leads from the branch 73 to a selective valve 79 through which fluid fuel is distributed from the carburetor to the various cylinders of the engine, and the preferred arrangement being that wherein the conduit 78 opens into a pipe 80 leading from the lower end of the heater 76 to the valve; it being apparent that, with this arrangement, the fuel may be delivered to the valve directly, or after being diverted through the heater.

80 To control the path of the fluid, I provide a valve 82 comprising a plug having a socket 83 in its inner end communicating with the channel 71 and having a port 84 adapted for communication with either of the branches 72 or 73; the end of the plug being projected through the end of the boss 70 and provided with a handle 85, whereby the valve may be turned to either position.

85 Interposed in the channel 71 is a throttle valve 87 having a lever 88 connected with the piston lever 22 by a rod 89, so that when the piston is lowered by vacuum in the intake manifold of the engine, the throttle valve in the fuel supply conduit is actuated to cut off and retard the otherwise too violent rush of air through the measuring device.

90 Referring now to the measuring device, 91 designates a seat in the upper portion of the case 36 above the measuring chamber 35, and 92 a plate supported on said seat and provided with a bearing 93. Revolubly mounted within the bearing 93, is a tubular shaft 94, which projects above and below the plate 92 and into a bearing socket 95 in the lower head of the cylinder 14; the disk and tubular shaft being concentric with the head bearing and inclosing the piston rod 32, which is adapted for free reciprocation within the shaft.

5 Fixed on the tubular shaft between the plate 92 and head 30 is a gear wheel 97 having a hub bearing within the socket in the cylinder head, and having peripheral teeth 98 meshing with a pinion 99 (Fig. VI), that is revolvably mounted in a recess 100 in a boss 101 on the cylinder, and fixed to a shaft 102 having bearing in said boss and projecting above and below the carburetor; the upper 10 end of the shaft being extended into the valve case 79 and operatively connected with the valve therein, as will presently be described.

15 The lower end of the shaft 102 has a beveled gear wheel 103 fixed thereon and meshing with a beveled gear wheel 104 on a shaft 105, which is revolvably mounted in bearings 106 on the carburetor and crank case, and provided with a sprocket wheel 20 107 having a chain 108 operatively connected with the crank shaft 109, so that the measuring mechanism and selective valve may be driven positively from the crank shaft, and thereby insure synchronism in 25 the measurement and distribution of fuel, and synchronism between such parts and the other parts operable from the crank shaft.

30 The rod 32 and tubular shaft 94 (Figs. IV, VIII and IX) project into a rectangular socket 110 in a drum 111, which is located in the measuring chamber 35 and fits snugly in a seat 112 therein, within which the channel 71 communicates; the 35 mouth of the channel being flared to increase its receiving area, and having a by-pass 114 leading up through the boss 70 to atmosphere; the by-pass being tapered from the channel to its mouth, in order to concentrate 40 the intake of air therethrough in order to facilitate the suction of liquid fuel from the measuring element when the parts are in operation.

45 The drum 111 is circular in cross section and revolves within the concave seat 112 and its periphery is provided with equally spaced longitudinal grooves 115 forming pockets for trapping fuel liquid and conducting same to the supply conduit leading 50 to the distributing valve when the drum is revolved; the drum being held to a close contact with its seat by a spring-pressed head 117 having a concave face bearing against the drum opposite the seat and having a socket 118 slidably mounted in a neck 119 on the side of the case 35; the head socket containing a spring 120, which bears 55 against the head and against a plug 121 that normally closes the neck 119.

60 In order to revolve the drum 111, I provide the tubular shaft 94 with arms 123, which extend into the ends of the socket 110 and are provided with rollers 113, so that

when the tubular shaft is revolved by the gear drive, heretofore mentioned, the drum 65 is revolved to carry fuel to the supply conduits; the rollers, however, being adapted for easy travel over the sides of the socket, so that the revoluble movement will not interfere with vertical reciprocation of the 70 drum.

By reference to Fig. IX, it will be noted that the length of the longitudinal pocket in the drum is slightly greater than the depth of the mouth of the off-take conduit, but 75 that the reciprocation of the drum is sufficient to carry the upper ends of the pockets below the top of the off-take mouth, and thereby decrease the area of registration and consequently the amount of fuel withdrawn 80 from the pockets, for the reason, that while the fuel located in the upper portions of the pockets will flow down into the off-take mouth, when the pockets are brought into registration with the mouth, suction in the 85 mouth will not lift the liquid from the bottoms of the pockets as there is no intake for air to the lower ends of the pockets.

With this construction it is, therefore, possible to regulate the delivery of fuel liquid 90 to the off-take conduits by reciprocating the piston, and for this purpose I connect the piston rod 32 with the measuring drum by attaching its lower end to a disk 124, that is fixed in the bottom of said drum by means 95 of the nuts 125, so that when the piston is drawn downwardly by vacuum in the intake manifold of the engine, the measuring drum is drawn downwardly to cut off the supply of fuel liquid, and when the vacuum is relieved and the piston raised under tension of the spring 22, the measuring drum rises to 100 supply the full volume of fuel.

Referring now to the preferred construction of the distributing valve, whereby the 105 various cylinders of the engine are served from a common supply pipe, 126 designates a valve case having outlet connections 127 corresponding in number to the number of cylinders in the engine; the present drawings illustrating four cylinders and their 110 outlets.

The case 126 is of inverted cup shape and has a boss 128 to which the supply pipe 80 is secured and having a central bore 129 for receiving fluid from the pipe 80, and delivering same to the interior of the case; the lower end of the case being covered by a plate 130, within which the shank 131 of a valve plug 132 is journaled.

115 The case 126 contains a head 133 having bores 134 registering with the outlet necks 127, and opening at their inner ends to a frusto-conical seat 135, the top of which communicates with the intake bore 129. 125 The plug 132 is also frusto-conical and fits

snugly against the seat 135, and is provided with a single bore 137 having a vertical leg 138 constantly registering with the bore 129 and a horizontal leg 140 adapted for registration with either of the outlet necks 127.

The shank 131 on the valve plug 132 has a socket 142 in its lower end, within which is keyed the upper end of the shaft 102, that drives the measuring drum as heretofore described; the rotation of the valve plug being facilitated by an anti-friction bearing comprising a ring 144, which is fixed to the valve plug and provided with a concaved outer face and a ring 145, which is mounted 15 on a spring plate 146 on the cover plate 130 and has a concaved inner face; the parts being so arranged that the concaved rings are spaced to carry the balls 147, and the spring plate or base being provided to yieldingly 20 tension the valve plug to its seat.

In order to secure the highest efficiency with the carburetor, I preferably provide the intake valve for each cylinder with a perforated cage 150 (Fig. XIV), which depends from the valve seat into the manifold tube, and project the vapor supply pipe through the cage at such an angle that when the valve lifts, the vapor may be discharged directly from the supply pipe through the 30 space between the valve and its seat, to inject the vapor directly into the cylinder without contacting with the valve head.

I also prefer to provide the fuel delivery pipe or nozzle 151 with apertures 152, which 35 are also inclined inwardly toward the valve, so that air contained within the manifold is drawn into the vapor tube and mixed therewith before the vapor is delivered into the cage where it is mixed with the greater supply of air.

It is apparent that, with this arrangement 45 vacuum created within the cylinder will act to draw vapor through the supply pipe and nozzle at a point directly adjacent the valve, thereby securing a more direct feed and more equal distribution.

In using the carburetor, presuming the parts to be constructed and assembled as described, when the engine is first started the 50 throttle 12 is opened and the piston 15 held to its upper limit by the spring 21, so that the pockets in the measuring drum present their full capacity to the out-take, through which fuel is delivered from the measuring 55 chamber to the cylinders. When starting with a cold engine, the valve 82 is turned to connect with the gasoline tank, so that the float and measuring chambers are filled with gasoline. When the engine is started 60 the pistons are reciprocated in the cylinders creating vacuum in the manifolds and in the supply conduit, the mouth of which is adapted to register with the pockets in the measur-

ing drum; the drum, meanwhile, being revolved through its gear connection with the 65 crank shaft. As the drum revolves, the pockets trap fuel against the seat 112 and carry same to the mouth of the out-take conduit, at which point vacuum in the conduit assisted by the free intake of air through the 70 by-pass, draws the liquid fuel out of the pockets in the measuring drum and conducts same through the pipe 78 to the distributing valve.

As the distributing valve is operatively 75 connected with the crank shaft, it also revolves synchronously with the operation of the other parts, so that its single channel constantly communicates with the supply pipe and with the pipes 127' leading to the 80 various cylinders in proper sequence, so that at the instant a valve in the cylinder is opened by vacuum created by descending pistons the distributing valve establishes communication between the pipe 127' from 85 that cylinder and the single supply pipe 80, and a charge of liquid fuel is pulled out of the pocket in the measuring disk, drawn up through the distributing valve and into the cylinder; each of the cylinders being supplied in like manner in proper sequence.

When the engine has been running for sufficient time to heat the cylinders and exhaust manifold, the valve 55 is turned to cut off the supply of gasoline and establish 95 communication between the kerosene tank and the float and measuring chambers, so that the heavier fuel may be used; the engine continuing to operate without interruption and without being affected by the 100 change of fuel, for the reason that the heavier oil being turned into the lower portion of the chamber carries the lighter liquid on top, until the latter is consumed.

When the valve 55 is turned to establish 105 communication with the kerosene supply, the valve 82 is also turned to direct the fuel liquid through the heater that surrounds the manifold pipe 77, so that a vacuum in the 110 cylinders will draw the fluid fuel from the measuring chamber through the heater to the distributing valve, instead of directly from the measuring chamber to the distributor.

Kerosene drawn from the measuring 115 chamber is vaporized in the heater, so that it reaches the distributing valve in the same or better condition for mixing with air in the manifold than the gasoline drawn from the measuring chamber; the operation of the 120 engine, except for the variation in fuel being the same, however, for either the light or relatively heavy liquid.

When the engine is running, increased 125 vacuum in the manifold due to closing of the throttle or rapid reciprocation of the pistons

in their cylinders, is by-passed from the auxiliary valve chamber to the cylinders 14 beneath the piston 15 and tends to draw the piston down against the tension of the 5 spring 22. This lowering of the piston has two effects, the first being that the measuring drum is lowered through the lowering of the rod 32, thereby moving the bottom line of the measuring pockets below the bottom 10 line of the mouth of the out-take conduit, so that as the pockets of the measuring drum are successively brought into registration with the mouth of the out-take conduit, a less quantity of fuel liquid is withdrawn 15 therefrom, for the reason, that as the lower ends of the pockets are closed, vacuum in the out-take conduit cannot draw liquid therefrom and the supply is thereby limited to the volume of liquid contained in the 20 pockets above the level of the mouth of the out-take conduit; this reduction in the supply of fuel obviating the tendency to flood the carburetor while the engine is running at high speed; it being apparent that the supply 25 of liquid is governed directly by the vacuum in the cylinders. The other result, following the lowering of the piston 15, is that as the piston lowers the rod 89 connecting the lever with the fuel throttle valve 87, 30 the raised end turns the valve across the out-take conduit, thereby shutting off the supply of air from the by-pass 114, and serving as a baffle to retard and spray the liquid fuel as it is taken into the out-take conduit under 35 the strong vacuum that is generated in the cylinders when the engine is traveling at high speed.

When the engine is stopped after being run on kerosene, it may be started again on 40 the same fuel, if the parts have not had sufficient time to cool, but with a cold engine it is preferable to first drain the float and measuring chambers of the kerosene and then start on the lighter fuel.

45 It is apparent that the present construction not only provides a simple and efficient apparatus for utilizing kerosene as fuel, but also provides means for regulating the supply of liquid to meet the varying requirements of the motor.

Having thus described my invention what I claim as new therein, and desire to secure by Letters Patent, is:—

1. The combination with an engine comprising a plurality of cylinders, an exhaust manifold communicating with said cylinders and having a pipe leading therefrom, an inclosed cage surrounding the pipe, a distributing valve having individual conduits 55 leading to the separate cylinders, a conduit leading from the bottom of said cage to the valve, a fuel measuring device, and a conduit leading from the measuring device to

the top of said cage, substantially as set forth.

2. The combination with an engine comprising a plurality of cylinders, an exhaust manifold communicating with said cylinders, and having a pipe leading therefrom, an inclosed cage surrounding the pipe, a distributing valve having individual conduits leading to the separate cylinders, a conduit leading from the bottom of the cage to the valve, a fuel measuring device, a conduit leading from the measuring device to the top of said cage, a separate conduit leading from the measuring device to the valve connection, and means for directing flow from the supply pipe through either of said conduits.

3. The combination with an engine comprising a plurality of cylinders, of a manifold having branches leading to each of the cylinders, a single air valve on the manifold, fuel supply conduits opening into each of said branches, adjacent their respective cylinders and a distributing valve communicating with said fuel supply conduits.

4. The combination with a multiple cylinder engine, of an intake manifold leading to all of the cylinders, an air valve in said intake manifold common to all of the cylinders, a fuel measuring device, conduits opening into said manifold adjacent each of said cylinders, and a distributing valve communicating with said measuring device and said conduits for delivering measured quantities of fuel to each cylinder.

5. The combination with a multiple cylinder engine, of an intake manifold having branches leading to each of the cylinders, an air valve for regulating the absolute pressure in said manifold, a distributing valve, conduits leading from the distributing valve to each of the manifold branches, a fuel measuring device, and a conduit leading from the measuring device to the distributing valve, whereby measured charges of fuel are delivered to said distributing valve.

6. The combination with a multiple cylinder engine, of an intake manifold having branches leading to each of the cylinders, an automatic valve for regulating the absolute pressure in said manifold, a fuel measuring device, and a distributing valve for successively connecting the several manifold branches with said measuring device.

7. The combination with a multiple cylinder engine, of an intake manifold having branches leading to each of the cylinders, an automatic valve for regulating the absolute pressure in the intake manifold, a fuel measuring device, a distributing valve, conduits connecting said measuring device and distributing valve and manifold branches,

and means for actuating said distributing valve, whereby said conduits are successively opened to the absolute pressure in the intake manifold and to said measuring device.

8. The combination with a multiple cylinder engine, of an intake manifold having branches leading to each of the cylinders, a distributing valve, conduits leading the 10 distributing valve to each of the manifold branches, a measuring device for measuring predetermined quantities of fuel, a tube connecting said measuring device with said

distributing valve, and an automatic valve for reducing the absolute pressure in said intake manifold to draw said measured charges of fuel successively into the manifold branches as determined by said distributing valve.

In testimony whereof I affix my signature 20 in presence of two witnesses.

CALEB E. SUMMERS.
